CLAIM

The ornamental design for a dish caddy, as shown and described.

DESCRIPTION

FIG. 1 is a top, front and right side isometric view of a dish caddy showing my new design;

FIG. 2 is a bottom, rear and right side isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a cross-sectional view taken along line 9-9 of FIG. 3; and,

FIG. 10 is a cross-sectional view taken along line 10-10 of FIG. 3.
